Williams Worley of New York City
Settler Posture

The device referred to in the above titled and making part of the same, containing a description in the words of the said Williams Worley himself, of his improvement in the Posture which he denominates the "Improved Posture or Hospital Posture."

To all whom these presents shall come. Be it known that I Williams Worley of the City County and State of New York, have invented a new and valuable improvement in the construction of a Posture for the sick or wounded, and that the following is a full and exact description of the construction and operation of said improvement as invented by me.

This new and valuable improvement is constructed in a frame similar to the common post Bedstead, now in use. It presents the valuable principle of being converted into an easy chair when one is required.

It consists in the first place of two movable bars, or frames, one of which is attached to the head, and the other to the foot of the frame before mentioned, these bars are movable similar to those of a table, placed in a receded position, and rest when drawn upon the cross bars at the head and foot of the frame. The sinking is secured at the head and foot to bars, made to fit within the holes. These bars are bowed to allow of the bars at the head and foot, and parallel to them, supported by common bed screws passing through both, which afford the facility of lightening the sinking at pleasure. This lightening principle is also applied to the bars of the sinking, by means of short bars, placed between the ends of the bars, and secured (by screws in the same way as the head and foot) to the center of the parallel bars of the frame. This forms the last of the bars when required.

To convert the Posture into an easy chair, instead of simply bars between the posts at the foot of the frame. There is a pin which passes through the post or frame at the foot and cuts a hole for the pin, placed in the bar. This pin is mounted at pleasure, and when withdrawn the foot bar falls down at right angles. The bars being drawn by means

Worley's Posture

of arms which form a visiting place within the head posts. These ends are wound on a drum, or shaft, by a crank, under the whole. The improved chair bed instead preserves also the invariable principle of raising the Patient without inconvenience, when evacuation by stool is necessary.

This is effected by having a light stuffed and quiltedacking above the bed which has an aperture in the centre for the convenience of the Patient. This is wound at the ends by loops, to the leaves, at the sides, there are two arms which extend inclined from the head leaf nearly to the foot where they are suspended by a cord attached to the foot post.

They are wound at the head by pivots or bolts, to the sides of the leaves. To each side of the upperacking and at proper distances apart, are two loops, which before the patient is raised must be placed over the corresponding - knot, in the arms before mentioned. off the crank then be turned, the bars at the sides, are elevated with the head leaf, and raise with them the upperacking of the necessary height to insert under it a bed pan or other utensil. The arms at the sides also serve as a rest for the patient when sitting up. To dispense with the cords, and crank, the arms may be furnished with a rock, to catch over a bolt at the foot of the frame. In this case the head leaf is raised by hand.

The subscriber claiming the priority of applying his improved Bed-
chairs for hiding the scrotum and balls, in his.

This improvement consists of a square piece of tin or other suitable metal, with the lower edge and sides bent over so as to form a groove, and a hole in the centre of sufficient size to admit the screw. These are fastened on with tacks over the scrotum hole, and another piece of the same metal is slid into the groove, and conceals the screw from sight. The whole should be japanned or painted.
